UNITED STATES PATENT OFFICE.

PETER GENDRON, OF TOLEDO, OHIO.

DESIGN FOR A CANOPY-TOP FOR CHILDREN'S CARRIAGES.

SPECIFICATION forming part of Design No. 17,893, dated November 22, 1867.

Application filed October 18, 1867. Serial No. 252,765. Term of patent 3½ years.

To all whom it may concern:

Be it known that I, PETER GENDRON, a citizen of the United States, residing at Toledo, in the county of Lucas and State of Ohio, have 5 invented and produced a new and original Design for Canopy-Tops for what are commonly known as "baby-carriages," of which the following is a specification, reference being had to the accompanying drawing, forming a 10 part thereof.

The leading feature of my design consists in rectangular short sections of curtains midway of the sides and ends of the canopy roof or frame, and having around the corners of 15 the frame lambrequins, both curtains and lambrequins being trimmed with lace or fringe, and the ends of the lambrequins overlapping the adjacent ends of the curtains.

A is the top or roof of the canopy, the frame 20 having rounded corners, as shown.

B is the side curtain or valance, of uniform width, its lower edge being trimmed with fringe or lace and placed midway between the

ends, and extends but a portion of the length of the side. Of course there is a corresponding curtain on the opposite side. 25

C is a similar but shorter curtain for the ends of the canopy, and it is midway of the end to the top and extends but over a portion of the ends. 30

D are the corner lambrequins, trimmed with lace or fringe, appearing to be continuous with the sides and ends of the top, the ends of such lambrequins overlapping the adjacent ends of the curtains, as shown. 35

What I claim is—

The design for a rectangular canopy-top of a carriage, as herein shown and described, consisting of the curtains on the sides and ends and the continuous overlapping lambrequins at each corner only, as shown. 40

PETER GENDRON.
